MEANS FOR ACOUSTICAL CORRECTION

Application filed July 18, 1929. Serial No. 379,273.

This invention relates to means for acoustical correction.

It is among the prime objects of the present invention to provide a novel and improved sound-deadening member which will absorb sound waves and prevent improper reflection thereof.

A further object of the present invention is to provide a sound-deadening member having maximum sound-deadening surface within minimum dimensions.

A further object of the present invention is to provide a device of the character described, which includes associated portions having variously characterized sound wave deadening properties, whereby the device will operate to deaden sound waves of widely varied frequency.

A further object of the present invention is to provide a device of the character described including a backing member and extending low frequency deadening members with which high frequency deadening members are associated, whereby the whole forms a novel, improved and compact structure designed to deaden sound waves of varying frequencies.

Other objects of the present invention include the combination and interrelation of parts whereby the whole forms a novel, simple and improved construction readily designed to meet the demands of economic manufacture.

Further objects and advantages of the present invention will be apparent from a consideration of the following specification taken in conjunction with the accompanying drawings, in which

Figure 1 is a top plan view of one form of the present invention, and

Fig. 2 is a side elevation broken away, as indicated by the lines 2—2 in Fig. 1.

Referring more particularly to the drawings, the preferred embodiment of the present invention as here illustrated, includes a casing member 10 having extending peripheral edges 11, whereby the device provides a substantially box-like casing, the top of which may be suitably closed by an artistically designed grille 12, the edges of which

may be secured to the edges 11 of the body.

In the embodiment of the invention herein shown the body and edges thereof are formed integrally of suitable sound-deadening material, it being preferable to employ material having a low natural period of vibration, such as the various fibre boards now on the market or any other equivalent cellular material. It is understood that the present invention is not confined to the specific range of frequencies to which the body is formed nor to the material of the body. It will be understood that if desired the body and side walls thereof may be a simple metallic casting without any effective free period of vibration. In such a case, it will be understood that the ribs or bridges, as will be hereinafter described, will have characteristic frequency resonance to accomplish the desired ends. The grille 12 may be of any desired artistic design and may be formed of any desired material, it being understood that the grille will not in usual constructions of the device, have an active part in the sound deadening.

Associated with the backing of the body and extending outwardly therefrom to an extent preferably less than the sides 11, a plurality of ribs or bridges 13 are provided. In the preferred form of the invention here illustrated, the bridges 13 are formed integrally with the body, it being understood that the body and bridges are formed of a low frequency resonant material. If desired, however, the bridges may be formed separately and associated with the body, in which case the body may be formed of metal or other non-resonant material as herein-after described. The arrangement of the bridges 13 is such that they provide a plurality of spaced troughs 14 therebetween.

Associated within the body and with the ribs 13, a high frequency responsive deadening material, such as felt or the like, is provided as indicated by the numeral 15. The high frequency absorbing material is laid within the troughs 14 formed by the ribs 13 and extends over the ribs and into the next adjoining trough in such a manner that a continuous piece of the felt may be used.

extending entirely across the device. The material 15 may be secured within the device in any suitable manner such as by gluing, or if desired by other equivalent securing means.

In the operation of the device, it will be understood that the device may be secured to a wall, ceiling or the like, by suitable securing means which may extend through apertures 16 in corners of the device. The grille 12 is designed to permit the free entrance of sound waves to the inside of the body, and, at the same time, provides an artistic covering for the body. As sound waves enter the body, the high frequency material, such as felt, indicated by the numeral 15, will absorb and deaden the high frequency sound waves and will prevent their reflection from the device. The low frequency waves would normally be reflected from the single high frequency felt, but in the present instance due to the support of the felt by the low frequency ribs 13 of the body 10, the body and/or ribs will operate with the felt to absorb and deaden the low frequency waves. Thus in the simple structure herein presented, both high and low frequency waves will be absorbed and deadened by the device. It will be understood that intermediate or parasitic waves will also be largely absorbed due to the fact that no sharp line of division between the absorption powers of the low and high frequency materials will be found.

The present invention not only provides a structure embodying co-operatively acting low and high frequency deadening materials, but by the construction of the device, a maximum sound-absorbing surface is provided within minimum dimensions of the device. It will be seen that by the ribs 13 and troughs formed thereby, the felt is laid in wave formation over the ribs to provide crests and hollows which materially increases the sound-deadening surface provided.

From the foregoing it will readily be seen that the present invention provides a novel, simple and improved construction which will be efficient in operation and well designed to meet the demands of economic manufacture.

It will be understood that the invention is not confined to the specific structure or materials herein recited, but that numerous changes and modifications and the full use of equivalents may be resorted to without departing from the spirit or scope of the invention as outlined in the appended claims.

What is claimed is:

1. A device of the character described, including a body, low frequency sound-deadening members on said body, and high frequency sound-deadening material applied to and conforming to the shape of the body and said members.

2. A device of the character described, in-

cluding a body, low frequency sound-deadening members in said body, and high frequency sound-deadening material associated therewith, said low frequency members including extending ribs carried by the back of said body, said high frequency material being laid over said ribs to provide a crest-and-hollow receiving surface.

3. In a device of the character described, the combination with a body, of a plurality of outstanding ribs on the body having low free periods of vibration whereby said ribs will act to absorb and prevent reflection of low frequency sound waves, and means applied to and conforming to the shape of said ribs and the body for preventing reflection of high frequency sound waves.

4. In a device of the character described, the combination with a body, of a plurality of outstanding ribs having low free periods of vibration whereby said ribs will act to absorb and prevent reflection of low frequency sound waves, and means associated with said ribs for preventing reflection of high frequency sound waves, said means comprising a high frequency absorbing felt associated with said ribs.

5. In a device of the character described, the combination with a body, of a plurality of outstanding ribs having low free periods of vibration whereby said ribs will act to absorb and prevent reflection of low frequency sound waves, and means associated with said ribs for preventing reflection of high frequency sound waves, said means comprising a high frequency absorbing felt associated with said ribs and laid thereover to provide a corrugated sound-receiving surface.

6. In a device of the character described, a low frequency resonant body having extending ribs formed integral therewith, and material applied to and also conforming to the shape of said body and ribs for absorbing relatively high efficiency sound waves.

7. In a device of the character described, a low frequency resonant body having extending ribs formed integral therewith, and high frequency responsive felt carried by said ribs.

8. In a device of the character described, a low frequency resonant body having extending ribs formed integral therewith, and high frequency responsive felt carried by said ribs, said felt being associated with said ribs and with the back of said body to provide a corrugated sound receiving surface.

9. In a device of the character described, a low frequency resonant body having extending ribs formed integral therewith, and high frequency responsive felt carried by said ribs, said felt being associated with said ribs and with the back of said body to provide a corrugated sound receiving surface, and an ornamental grille carried by said

body, said grille permitting the passage of sound waves therethrough.

10. A device of the character described, including a frame having a rear wall, forwardly extending side walls, and integral parallel ribs within said walls, felt sound-deadening material within said body extending over said ribs to provide a felt corrugated sound-deadening surface, and an apertured cover plate for said body secured to said side walls in spaced relation to the ends of said corrugations.
